his Attorney.

UNITED STATES PATENT OFFICE.

ARTHUR GARFIELD REMHILT, OF PHILADELPHIA, PENNSYLVANIA.

SIGNAL DEVICE.

Application filed July 18, 1921. Serial No. 485,591.

To all whom it may concern:

Be it known that I, ARTHUR GARFIELD REMHILT, a citizen of the United States, residing at Philadelphia, in the county of Philadelphia and State of Pennsylvania, have invented certain new and useful Improvements in Signal Devices, of which the following is a specification.

One object of my invention is to provide a signal device of exceptionally simple construction which can be used with advantage on automobiles or other vehicles for the purpose of clearly indicating the intentions of the driver, of the vehicle upon which the device is mounted, to turn to the right or to the left, to stop, or any other signal which it is desired to give.

Another object is to so make the device of my invention that it will be neat in appearance and light in weight.

These objects, and other advantageous ends which will be described hereinafter, I attain in the following manner, reference being had to the accompanying drawings in which—

Figure 1 is a front elevation showing my improved signal device illustrating the same connected to a part of a vehicle; said part being illustrated in section,

Figure 2 is an enlarged sectional view taken on the line 2—2 of Figure 1,

Figure 3 is a sectional view taken on the line 3—3 of Figure 2 and showing the same on a slightly reduced scale,

Figure 4 is a face view of a disk which forms a part of my invention,

Figure 5 is a face view of a portion of said device illustrating the same as it actually appears when displaying a signal, and

Figure 6 is a fragmentary section showing a slight modification in the manner of securing the parts of the case together.

Referring to the drawings, 7 represents a case which is circular in form and includes two circular plates or disks 8 and 9 which are preferably made out of thin sheet metal having their peripheral edge portions bent inwardly to provide contacting flanges 10 which may be soldered or spot-welded in the form as shown in Figures 1 to 5 inclusive. Or as shown in Figure 6, these flanges may be overlapped so as to snugly fit one within the other. The circular plates 8 and 9 are placed in axial alignment and are closely positioned so as to provide a com-

paratively narrow space 11 in which is positioned a disk 12. This disk 12 may be made of metal, sheet fiber or any other suitable material and has its opposite faces arranged with a dark sectoral portion 13 and a white or light colored sectoral portion 14 as shown in Figure 4; the opposite faces of the disk being the same. In making this disk I can paint the portion 13 black or any suitable dark color and the portion 14 can be made white. The outer surfaces of both of the plates 8 and 9 are made dark such for example as by painting them black or a dark color. Each of these plates 8 and 9 is also perforated to provide any suitable signal representation such for example as the arrows 15 and 16 and the word "Stop." The surface portions 14 on the opposite faces of the disk 12 is made small compared to the dark portions 13; the relative proportions between the portions 13 and 14 being such that the portions 13 can extend entirely to the rear of the arrows 15, 16 and the word "Stop" as is shown in Figure 1. However, the area and shape of the portions 14 of the disk are such that if the disk is rotated relatively to the case 7, said portions 14 are capable of forming a backing visible through any of the arrows 15 or 16 or through the word "Stop"; thus permitting the perforated arrows or the word "Stop" to appear distinctly visible as is noted by the showing in Figure 5.

The disk 12 is rotatably supported within the case on a stud pin 17 which extends through the plate 8, the plate 9 having a screw 18 extending therethrough and engaging a tapped hole in the inner end of the stud pin 17. This stud pin extends freely through a hole 19 in the disk and thus the disk has a rotatable bearing on the stud pin 17. A small gear wheel 20 is secured to the disk 12 and has a hole through which the stud pin 17 extends. This gear wheel 20 meshes with another gear wheel 21 as shown in Figures 2 and 3; the gear wheel 21 being rotatably supported on a stud screw 22 which passes through the plate 9. The plate 9 is preferably provided with a recess 23 which can be formed by stamping or pressing the material of the plate 9 so as to make an engagement capable of accommodating the gears 20 and 21 and also serving as a means for receiving a hanger bearing 24 which supports a toothed rack 25.

which operatively connects with the gear wheel 21. The rack 25 has a portion 26 which extends out of the case and I have shown the case supported by a bracket 27 which 5 may be of any suitable type capable of being secured to a part of the vehicle such for example as the part 28. In the form illustrated the bracket 27 has a sleeve portion 29 through which the part 26 of the rack 10 25 slides and upon this portion 29 is secured a depending member 30 having a notched segment 31 on its lower end. A lever 32 is pivoted at 33 between its ends to the member 30; said lever having a slot 34 through 15 which a pin 35 on the rack portion 26 extends. The lower end of the lever 32 has a spring-pressed plunger 36 adapted to engage any one of the notches 37 in the segment 31 and thereby hold the lever 32 in any position 20 into which it is moved. It is obvious that when the rack 25 is moved lengthwise it will rotate the disk through the medium of the gear wheels 21 and 20; the direction of the rotation of the disk depending upon the 25 direction in which the rack is moved.

The arrangement and proportion of the parts is such, as illustrated that the white portions of the disk can be moved from the position shown in Figure 1 into registry 30 with the apertures 15 or 16 or into registry with the apertures forming the word "Stop." Thus considering that the outer surfaces of the plates 8 and 9 of the case 7 are made black or a dark color, when the portions 14 35 are moved into registry with any of the above mentioned apertures, said apertures will be distinctly visible owing to the fact that a white or light colored surface is visible therethrough. Further considering that 40 both sides of the device are alike, signals of light character will be displayed both from the front and the rear of the device.

If desired the portions 14 can be painted with a luminous paint such for example as 45 a radium luminous paint and as such will be distinctly noticeable at night or the outer faces of the case can be illuminated by small lamps (not illustrated) so that the signals will be visible at night as well as during the day. It will be noted that the 50 portion 14 on each side of the disk is of sufficient area to cover only one of the apertures at a time so that there is no possibility of any confusion of signals when the device 55 is operated and the arrangement of the notches 37 serves as means for determining the proper location of the portion 14 of the disk and the stopping of the rotatable movement of the disk.

60 It will be noted, broadly speaking, that the portions 14 of the disk are of a contrasting character to the eye compared with the character of the outer surfaces of the plates 8 and 9 and the portions 13 of the 65 disk.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, 75 what I claim as new and desire to secure by Letters Patent is:—

1. A device of the character described including a case having perforations in its front and rear indicating visible signal portions; and a member movable within said case having on its opposite parts portions of reflective and comparatively non-reflective character, said member being optionally movable into registry with said perforations of the front and rear of the case to expose any one of said signal perforations with said reflective portion; substantially as described. 85

2. A case having arrow-shaped perforations therein pointing toward the right and 90 toward the left and a perforation for a stop signal; and a member movably mounted within said case and having a large dark portion to cover all of said signal perforations and a small light portion to set across 95 either signal to render such signal effective; substantially as described.

3. A device of the character described including a case having perforations in its front and rear indicating visible signal portions; and a disk rotatably mounted within 100 said case and having its opposite surfaces in planes approximately parallel with and adjacent to the inner surfaces of the front and rear of the case, said surfaces of the disk having sectoral portions of reflective and comparatively non-reflective character and optionally movable into registry with 105 said perforations of the front and rear of the case; substantially as described. 110

4. A device of the character described including a case having perforations therein indicating visible signal portions; a member movable within the case having portions of reflective and comparatively non-reflective character and optionally movable into registry with 115 said perforations; means for effecting rotation of said member and means whereby said last named means can be held in any position into which it is moved; substantially as described.

5. A signal device including a case of opaque material having open transparent portions representing signals, and a member movable within the case and having dark 125 and light portions, the dark portion being designed to cover all of said signal representations simultaneously and to uncover the same independently whereby the signal representations may be independently viewed 130

at the light portion disposed in registry with any of the uncovered signal representations.

6. A signal device of the character described including a circular case having opposed plates of opaque material provided with perforations indicating visual signal portion; a disk rotatable in said case and having a large sectoral portion of comparatively non-reflective character adapted to cover all of said signal portions simultaneously, and a small sectoral portion of re-

flective character adapted to independently disclose to view each of said signal portions while the other portions are covered by the larger non-reflective portion of the disk. 15

In testimony whereof I have signed my name to this specification in the presence of two subscribing witnesses.

ARTHUR GARFIELD REMHILT.
